SELF-DUMPING RAG CATCHER

Application filed June 3, 1927. Serial No. 196,177.

My present invention relates in general to improvements in paper making equipment and has particular reference to an improved means for removing rags and other foreign substances from beater tubs and transferring them to a cart, trough, or something of that kind for disposal.

As heretofore practiced, the rags and other foreign substances have been removed from the beater tub by more or less laborious methods requiring the services of individuals and makeshift equipment, so to speak. One of the principal objects of my invention is to accomplish automatically what has heretofore been carried out manually and thereby increase the efficiency of the existing equipment with a resultant saving in labor and time.

The preferred embodiment of the invention is illustrated in the accompanying drawing in which:

Fig. 1 is a view in front elevation of my improved apparatus, which I will hereinafter identify as a self-dumping rag catcher;

Fig. 2 is a side elevation of the apparatus with the rag handling carriage thereof in position to collect the rags from the beater tub;

Fig. 3 is a similar view with the carriage in an elevated dumping or unloading position;

Fig. 4 is a cross section taken on the line 4—4 of Fig. 1; and

Fig. 5 is a detail view in section of one of the rollers for the carriage dumping device.

Referring now to the drawings in detail, 5 and 6 represent a pair of channel members, the spaced positions of which are intended to fit the inside width of a beater tub with ledges 7 on the members to rest upon the edge of the tub so that the self-dumping rag catcher may be vertically supported over the tub. The channel members 5 and 6 are arranged with their recesses facing one another and they are joined at their upper ends by horizontal channels 8 and 9, which lay flush with their narrow sides. Mounted upon the top of the frame structure provided by the members 5 and 6 and the channels 8 and 9, is a rotatable shaft 10, the same being journaled

in the bearings 11 and 12 which in turn are supported by the I-beam supports 13 and 14 upon the top of the frame structure. Mounted on the free end of the shaft 10 to rotate therewith is a flanged cable drum 15. A like drum 16 is mounted to the shaft on the outside of the bearing 12. The shaft may be driven by a reversible motor (not shown) connected by a belt to a belt pulley 17 which is connected to the shaft 10 through a reduction gear unit 18.

Wound upon the drums 15 and 16 are cables 19 and 20 the unwound ends of which being connected to the inverted U-hangers 22 and 23 on the rag catcher carriage which is mounted between the vertical side members 5 and 6.

The carriage is provided with two sets of wheels or rollers 24 and 25 and the recesses of the channel members 5 and 6 provide tracks 70 for the same so that the carriage may be elevated and lowered with respect to the frame by the reversible motor above referred to.

The carriage includes a lower horizontal channel member 26 to which the wheels 25 are mounted by straps 27 and 28 or any other means suitable for the purpose. The upper horizontal frame member 29 carries the rollers 24 and the hangers 22 and 23 for the cables 19 and 20. With this arrangement, the rag carriage is thus mounted to be elevated and lowered between the members 5 and 6 so that the fingers or tines 30 thereon may be lowered into the beater tub for collecting and raising the rags out of the tub.

The fingers are mounted in spaced parallel relation upon the frame so that their curved lower extremities project in front of the apparatus. The mounting for the fingers may be accomplished by providing a series of angle cleats 31, one face of each cleat being secured to the depending flange on the channel member 26 and the other faces of the cleats lying flush with and secured to the sides of the upstanding parts of the finger 30. The upper ends of the fingers are secured to the frame member 29 in any suitable manner and some of the fingers extend past the member 29 and have transverse openings for the reception of a horizontal rod 32.

The above description explains the construction of the rag catcher. In operation, it is supported over the beater tub as above explained, and, by operating the reversible motor (not shown) in one direction, the carriage 5 may be lowered into the tub by the cables 19 and 20 so that the fingers 30 thereof may collect a quantity of the rags contained in the tub. By reversing the motor, the carriage 10 may be elevated from the tub with a batch of material carried by the fingers.

In my co-pending application, Serial No. 196,178, filed June 3, 1927, I have shown a similar rag catcher equipped with a spraying apparatus to spray the material as it is lifted out of the tub. In this case, I have combined the rag catcher with a dumping apparatus so that it thus becomes a self-dumping rag catcher. In this connection, I wish to make it clear that I may use the rag catcher apart from a spraying apparatus or apart from a dumping apparatus or I may use both the dumping apparatus and spraying apparatus in connection with the rag catcher.

When the rags are lifted out of the tub by the fingers of the rag catcher carriage, it has been heretofore necessary to drag them off the fingers by rakes or other improvised manually manipulated means so as to deposit them on trays, carts, or the like.

In accordance with the present invention, I have devised a means of automatically dumping the material at the desired stage in the operation of the rag catcher so that this particular operation may thus be accomplished mechanically without the aid of an individual. As a result, I am enabled to effect a saving in time and expense in the operation of this kind of equipment.

My improved dumping apparatus preferably comprises a series of dumping arms or the like 33 which are mounted on the rag catcher carriage to normally assume an inactive retracted position behind the curved ends 45 of the fingers 30. Means are arranged to move these arms toward the finger ends so as to push the material off the fingers and upon a tray or cart or any other device to receive the same.

In order that the arms may function in this capacity, I prefer that they be pivotally mounted at their upper ends and arranged to lie parallel with the fingers 30 and even flush therewith. I would ordinarily use about one half the number of arms to that of the fingers so that an arm would lie adjacent every other one of the fingers. The length of the arms exceeds that of the fingers excepting those fingers with which the arms are directly associated. These particular fingers are the ones that engage the horizontal rod 32. This rod provides the pivoted mounting for the upper ends of the arms and for this connection the arm ends are made with openings like the 60 finger ends so that the rod may pass there-

through. The fingers, being made fast to the frame members of the carriage, are not free to move in advance of the carriage like the arms so that their position never changes except in a vertical plane. The arms 30 are 70 suitably braced by oblique angle members which cross one another. The faces of the angles are cut away or slotted at their intersection so as to enable the same to be mounted to the arms in the same plane.

To actuate the arms, each one is connected to a channel member 35 which extends rearwardly and upwardly of the carriage with their opposite end secured to a horizontal member 36. The two outer members 35 are secured to and extend past the member 36 to provide a mounting for the rollers 37 and 38. The rollers in this respect being journaled between the members which support them and the brackets 39 and 40.

Mounted to the back of the upright frame members 5 and 6 and depending downwardly thereof are a pair of oblique channel tracks 41 and 42 for the rollers 37 and 38. These tracks are properly braced by a horizontal angle member 43 and a pair of vertical angle members 44 and 45.

The lower ends of the tracks 41 and 42 are abruptly turned downwardly so as to confine the rollers in the channels thereof.

Extending from the channel members 35 to the arms 30 are a series of additional bracing angle members 46 which cooperate with the member 35 in imparting the necessary thrust to the arms for dumping purposes. With this arrangement, a thrust is imparted to the arms at spaced distances in their length and develops a decided rigid and positive connection for this purpose. A horizontal rod 47 is also employed to brace the members 36 and the parts associated therewith.

In the operation of the rag catcher when the carriage is lowered into the beater tub, the rollers 37 and 38 are at the lower end of the tracks 41 and 42. When the carriage is elevated, the rollers 37 and 38 are caused to travel upward on the tracks 41 and 42 and the oblique angle of the tracks results in an outward thrust being imparted to the pivoted arms 33 so that they may move toward the curved ends of the fingers and wipe or push the material off the fingers. As the carriage is lowered, the arms are returned and reset in their normal retracted position where they do not in any way interfere with the operation of the fingers when collecting another batch.

The operation of the assembly is shown to advantage in Figs. 2 and 3 wherein Fig. 2 shows the arms in a position that they will assume when the carriage is lowered into the beater tub and Fig. 3 shows the carriage elevated and the arms projected forward at the limit of their active load dumping position.

Obviously those skilled in the art may make

various changes in the details and arrangement of parts without departing from the spirit and scope of the invention as defined by the claims hereto appended, and I wish therefore not to be confined to the precise construction herein disclosed.

I claim:

1. A self-dumping rag catcher, comprising a frame structure constructed to be positioned over a beater tub, a material handling carriage on the frame structure, means for elevating and lowering said carriage with respect to the beater tub, material collecting members on said carriage, and means associated with said carriage for removing the material collected by said members comprising a series of arms pivotally mounted on said carriage in association with said members, and means for projecting and retracting said arms with respect to said members.

2. A self-dumping rag catcher, comprising a frame structure constructed to be positioned over a beater tub, a material handling carriage on the frame structure, means for elevating and lowering said carriage with respect to the beater tub, material collecting members on said carriage, and means associated with said carriage for removing the material collected by said members comprising a series of arms pivotally mounted on said carriage in association with said members, and means for projecting and retracting said arms with respect to said members comprising an oblique track on the rag catcher frame, rollers disposed to travel said track, and a connection between said rollers and said arms.

3. A rag catcher of the class described having a material handling carriage, cables for elevating and lowering said carriage, winding drums for said cables, a shaft on which said drums are mounted for winding and unwinding the cables, and means on the carriage for removing material from a beater tub into which the carriage is lowered, comprising outwardly presented curved members mounted on the carriage in spaced relation, and pivoted arms mounted between said members for removing the material carried thereby when the carriage is elevated.

4. A rag catcher of the class described having a material handling carriage, cables for elevating and lowering said carriage, winding drums for said cables, a shaft on which said drums are mounted for winding and unwinding the cables, and means on said carriage for removing material from a beater tub into which the carriage is lowered, comprising outwardly presented curved members mounted on the carriage in spaced relation, and pivoted arms mounted between said members operated by the elevating of said carriage for removing the material carried by said members.

5. In a rag catcher of the class described, a

frame structure arranged to be positioned over a beater tub, a material handling carriage on said frame structure, a series of outwardly presented curved members mounted on said carriage in parallel spaced relation, means for lowering said carriage into the beater tub to remove material therefrom with said members, and means for wiping the material from said members when the carriage is elevated from the beater tub comprising a series of arms pivoted to said carriage between said members, and means for projecting said arms between said members toward the curved extremities thereof.

6. In a rag catcher of the class described, a frame structure arranged to be positioned over a beater tub, a material handling carriage on said frame structure, a series of outwardly presented curved members mounted on said carriage in parallel spaced relation, means for lowering said carriage into the beater tub to remove material therefrom with said members, and means for wiping the material from said members when the carriage is elevated from the beater tub comprising a series of arms pivoted to said carriage between said members, and means for projecting said arms between said members toward the curved extremities thereof comprising rollers, a connection between said rollers and said arms, tracks for said rollers mounted on the rag catcher frame, said tracks being disposed at an angle to said carriage, whereby the elevating of the carriage will cause the rollers to traverse the tracks and move said arms toward the ends of the curved members.

7. In a rag catcher of the class described, a material handling carriage mounted to be lowered into and elevated from a beater tub, material collecting members mounted in spaced relation on said carriage, and means mounted between said members for dumping the material collected thereby when said carriage is elevated.

8. In a rag catcher of the class described, a material handling carriage mounted to be lowered into and elevated from a beater tub, material collecting members mounted in spaced relation on said carriage, and means mounted between said members for dumping the material collected thereby when said carriage is elevated comprising pivoted arms, and means operated by the elevating of said carriage for swinging said arms toward the ends of the said members.

9. In a rag catcher of the class described, a material handling carriage mounted to be lowered into and elevated from a beater tub, material collecting members mounted in spaced relation on said carriage, and means mounted between said members for dumping the material collected thereby when said carriage is elevated comprising a series of connected arms alternating with said members and pivoted at the top of said carriage, and

an operating connection between said arms and the rag catcher for moving said arms toward the ends of said members when said carriage is elevated.

5 10. In a rag catcher of the class described, a material handling carriage mounted to be lowered into and elevated from a beater tub, material collecting members mounted in spaced relation on said carriage, and means

10 mounted between said members for dumping the material collected thereby when said carriage is elevated comprising a plurality of arms pivoted to swing in the spaces between said members, and means for projecting and

15 retracting said arms between said members when said carriage is lowered and elevated.

11. In a rag catcher of the class described, a material handling carriage mounted to be lowered into and elevated from a beater tub,

20 material collecting members mounted in spaced relation on said carriage, and means mounted between said members for dumping the material collected thereby when said carriage is elevated comprising a plurality of

25 arms pivoted to swing in the spaces between said members, and means for projecting and retracting said arms between said members when said carriage is lowered and elevated comprising rollers with which the arms are

30 connected, and oblique tracks on the rag catcher on which said rollers travel.

In testimony whereof I have signed my name to this specification on this 31st day of May, A. D. 1927.

35 HARVEY E. MARVEL.
